CLAIM

The ornamental design for a frame grill plate for a motorcycle, as shown and described.

DESCRIPTION

FIG. 1 is a perspective view of a frame grill plate for a motorcycle showing our new design, with the broken lines showing environmental structure that forms no part of the claimed design.

FIG. 2 is a perspective view thereof.

FIG. 3 is a front view of the article in an upright position; and, FIG. 4 is a back perspective view thereof.
